WOMAN'S CAP

Carmella A. O'Searo, 1218 George St. Extension,
Sharon, Pa. 16146

Filed Dec. 11, 1969, Ser. No. 20,456

Term of patent 14 years

Int. Cl. D2—03

U.S. Cl. D2—250

FIG. 1 is a side perspective view of a woman's cap showing my new design, the side opposite thereto being reversely similar; and

FIG. 2 is a rear view of the cap.

I claim:

The ornamental design for a woman's cap, as shown and described.
